Primary Examiner — Clare E Heflin

(57) **CLAIM**

The ornamental design for personalizable lamp, as shown and described.

DESCRIPTION

1. Personalizable lamp
- 1.1 : Front
- 1.2 : Back
- 1.3 : Right and left view
- 1.4 : Top
- 1.5 : Bottom
- 1.6 : Perspective
- 1.7 : Enlarged

Fig. 1.1 is a front view of a personalizable lamp design, showing my new design; fig. 1.2 is a rear view thereof; fig. 1.3 is both a right and a left view thereof, the right and left sides being identical; fig. 1.4 is a top view thereof; fig. 1.5 is a bottom view thereof; fig. 1.6 is a perspective elevation view thereof; fig. 1.7 is an enlarged perspective view of detail "7" identified in fig. 1.6; the broken lines in the figures depict portions of the personalizable lamp that form no part of the claimed design.
